(57) CLAIM

The ornamental design for a lamp for vehicle, as shown and described.

DESCRIPTION

FIG. 1 is a front side perspective view of a lamp for vehicle showing my new design;

FIG. 2 is a rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawing views are included for the purpose of illustrating the unclaimed portions of the lamp for vehicle and form no part of the claimed design.
